SAFETY REVERSIBLE WINDOW

Louis I. Alperin, Scranton, Pa.

Application November 3, 1948, Serial No. 58,138

4 Claims. (Cl. 20—49)

1

My invention relates broadly to windows, and more particularly to an improved construction of hardware for converting existing double hung window sashes into swinging adjustable reversible sash windows.

My invention is directed to that class of reversible windows set forth in my Letters Patent 2,332,500 granted October 26, 1943, for Safety Reversible Window, and in Letters Patent 2,423,675 granted July 8, 1947, for Safety Reversible Window, and in my copending application for Letters Patent filed April 16, 1946, Serial Number 662,486, for Safety Reversible Window, which is now Patent No. 2,491,792 granted December 20, 1949.

One of the objects of the instant invention is to provide a construction of hardware applicable to existing types of double hung window sashes for converting such window sashes into swingable reversible sash windows for rendering both sides of the glass panes accessible from a convenient interior position for cleaning and facilitating adjustment of the swinging sashes for ventilation purposes where each sash is pivoted adjacent the upper and lower portions of the window frame.

Another object of my invention is to provide a construction of hardware for converting double hung window sashes into swinging reversible sash windows where the two sashes are pivotally mounted on horizontal axes immediately adjacent the upper and lower limits of the window frame, facilitating the tilting of the sashes with respect to the top and bottom of the window frame.

Still another object of my invention is to provide an improved structural arrangement of pivot means for safety reversible windows by which sash windows pivoted adjacent the upper and lower portions of the window frame may be adjusted to a selected angular position and maintained in the adjusted angular position, providing access to either side of the glass panes of the sash.

Still another object of my invention is to provide a novel construction of weather stripping for swinging sash windows wherein sash strips individual to each window sash carry weather stripping members which are projectable and retractable from the sash strips into the edges of the window sashes when the window sashes are moved to closed positions vertically slidable as a double hung window within a window frame.

Still another object of my invention is to provide an improved mechanism for controlling the position of weather stripping projectable and retractable with respect to opposite sides of window sashes of the double hung convertible type.

2

A still further object of my invention is to provide an arrangement of weather stripping members for composite swingable and vertically movable window sashes of the double hung type in which novel control means are provided adjacent the top of each window sash for projecting or retracting the weather stripping members from sash strips located in the stiles of the window frame with respect to the opposite edges of the window sashes for providing a weather-tight connection between the window frame and the sashes when the sashes function as a double hung window, while facilitating the conversion of the sashes to pivotally mounted units swingable from positions adjacent the top and bottom of the window frame.

Still another object of my invention is to provide a composite double hung vertically movable and angularly adjustable window sash construction which may be installed in association with storm sash equipped window frames where the storm sashes normally offer obstruction to the swinging movement of the window sashes, but wherein the construction of my invention permits angular displacement of the window sashes interiorly with respect to the window frame without obstruction to a storm window mounted exteriorly of the window frame.

Other and further objects of my invention reside in the construction and arrangement of double hung window sashes converted for reversible swinging movement, as set forth in the specification hereinafter following by reference to the accompanying drawings, in which:

Figure 1 is a front elevational view of a double hung and pivotally mounted window embodying my invention; Fig. 2 is a vertical sectional view taken substantially on line 2—2 of Fig. 1, with the double hung sashes shown in full line position for sliding movement within the window frame and illustrated in dotted lines to represent the manner in which the sashes may be adjusted to angular positions; Fig. 3 is an enlarged horizontal sectional view taken substantially on line 3—3 of Fig. 1, the view being foreshortened to enable the parts to be shown on a larger scale; Fig. 4 is a vertical sectional view on an enlarged scale with the view foreshortened and illustrating the double hinge window sashes each in position for vertical sliding movement within the window frame; Fig. 5 is a view similar to the view shown in Fig. 4 but illustrating the window sashes moved to angular positions extending interiorly of the building structure and without interfering with an externally mounted storm window or screen; Fig. 6 is a fragmentary vertical sectional view illustrating the extreme upper

position of the upper sash and showing the weather stripping control means, certain of the parts being illustrated in side elevation; Fig. 7 is a view similar to the view shown in Fig. 6 but illustrating the weather stripping member in projected position into the sash from the weather stripping member; Fig. 8 is a view similar to the view shown in Figs. 6 and 7, but illustrating the upper sash moved downwardly to a position in which the weather stripping member is retracted from the window sash so that the window sash is free to be angularly moved in the manner illustrated in Fig. 5; Fig. 9 is an enlarged view taken substantially on line 9—9 of Fig. 11 and illustrating the hardware employed for pivotally mounting the upper sash with respect to the associated sash strip, the parts being illustrated in the extreme upper position of the top sash; Fig. 10 is a front view similar to the view illustrated in Fig. 9 showing the upper sash moved to a position below the top of the window frame to permit access to the manipulator for controlling the retraction of the weather stripping member from the window sash preparatory to freeing the window sash for angular movement, the view being taken on line 10—10 of Fig. 12; Fig. 11 is a horizontal sectional view taken substantially on line 11—11 of Fig. 9 and illustrating the window sash in a position for vertical sliding movement in the stiles of the window frame; Fig. 12 is a horizontal sectional view taken substantially on line 12—12 of Fig. 10, but illustrating the window sash moved to an angular position with respect to the frame of the window; Fig. 13 is a horizontal sectional view taken substantially on line 13—13 of Fig. 9 and showing the abutting hardware on the sash strip and on the adjacent edge of the window sash in horizontal section; Fig. 14 is an elevational view of the hardware attached to the edge of the window sash; Fig. 15 is a vertical sectional view taken on line 15—15 of Fig. 14; Fig. 16 is a horizontal sectional view taken substantially on line 16—16 of Fig. 14; Fig. 17 is an elevational view of the hardware which is secured to the sash strip for coaction with the hardware illustrated in Figs. 14—16, which is secured to the sash; Fig. 18 is a vertical sectional view taken substantially on line 18—18 of Fig. 17; Fig. 19 is a horizontal sectional view taken substantially on line 19—19 of Fig. 17; and Fig. 20 is a horizontal sectional view taken substantially on line 20—20 of Fig. 17.

My invention is a substantial improvement over the safety reversible window constructions referred to in my hereinbefore cited Letters Patents and application for Letters Patent, in that I provide hardware for converting double hung vertically slidable window sashes into swingable sash windows movable about axes adjacent the top and bottom of the window frame. In my prior developments the sash windows have been pivoted along a horizontal axis centrally thereof so that each window sash is swingable both exteriorly and interiorly of the window frame. This is a substantial disadvantage where it is desired to utilize the advantages of the swingable sashes in installations where exterior storm windows and screens are mounted. By the arrangement set forth in my invention the sashes are each pivotally mounted for interior swinging movement and without exterior swinging movement, so that the sashes project interiorly through the frame but not exteriorly thereof throughout all positions of adjustment. Accordingly, storm windows with removable sashes and replaceable

screens may be installed. Inasmuch as there is no exterior movement of the sashes in accordance with the arrangement of my invention, no interference is offered to the installed storm window or associated window screens therein.

The double hung window sashes, after removal from the stiles of the window frame, are trimmed at opposite edges thereof and a sash strip applied to each edge thereof. The sash strips are vertically slidable in the stiles of the window frame. These sash strips each carry special hardware fittings each constituting an annular trackway on the sash strips for coaction with hardware members mounted on the opposite edges of the window sashes and having spaced cam members operative to enter the trackway in the hardware fitting carried by each sash strip. The hardware fitting carried by the sash strip is slotted centrally and vertically with respect to the sash strip, the slots being disposed in oppositely spaced positions of the circular trackway whereby the spaced cam members carried by opposite edges of the sashes are displaced transversely as the sashes are subjected to a swinging movement out of alignment with the sash strips. As the window sashes equipped with the hardware of my invention are displaced angularly, the spaced cam members are thrust away from the diametrically opposite slot portions of the hardware carried by the sash strips and revolve within the annular trackway of the hardware carried by the sash strip. The yieldability of the window frame construction is sufficient to permit this slight transverse displacement and allow the window sashes to be moved at an angle with respect to the sash strips and projecting interiorly from the window frame without interference to obstruction offered by the storm window or associated screen mounted therein.

The sash strips in my present invention also carry weather stripping members. Each weather stripping member is mounted in a longitudinally extending slot in the sash strip, and I provide means adjacent the upper end of each sash strip for projecting and retracting the weather stripping member with respect to the sash strip. Coacting with the projectable and retractable weather stripping member, I provide grooves in each edge of the coacting window sash. When these grooves are aligned with the weather stripping members carried by the sash strips, the weather stripping members may be projected from the sash strips into the edges of the sash. I provide various forms of manipulating means for projecting and retracting the weather stripping members. Also, I provide various arrangements of weather stripping members which may be projected or retracted from the sash strips into opposite edges of the sashes. Thus, weathertight joints are established and maintained between the sashes and the sash strips when the window sashes are moved to positions aligned with the sash strips and vertically movable as a double hung window in the window stiles.

Referring to the drawings in more detail, I have shown the hardware of my invention for converting double hung windows into modern swinging sash windows wherein reference character 1 designates the frame of a double hung window having vertically arranged stiles 2 and 3. The window sashes 4 and 5 are normally slideable in the vertically arranged stiles 2 and 3. In converting the double hung window to a swinging sash window in accordance with my in-

vention, each window sash is trimmed on each edge thereof for receiving a sash strip 6 and 7 coacting with window sash 5, and sash strips 8 and 9 coacting with window sash 4. The sash strips are vertically adjustable in the window stiles 2 and 3. The pairs of sash strips for each sash are controlled in vertical adjustment by means of sash cords and sash weights associated therewith. For example, the window sash 4 is provided with sash strips 8 and 9 which connect through sash cords 10 and 11 to sash weights 12 and 13. When sash strips 8 and 9 and the associated window sash 4 are in their lowermost position the weights 12 and 13 are in the positions illustrated in Fig. 1. Similarly, when window sash 5 is in its normal position the sash strips 6 and 7 connect through sash cords 14a and 15a to sash weights 14 and 15 operative within the window frame casing. The respective sash strips 6, 7, 8 and 9 connect with the coacting cords for effecting a controlled and balanced vertical movement of the sash strips and the window sashes associated therewith.

The window sashes are each provided at the cutaway edge portions thereof with special hardware fittings illustrated more clearly in Figs. 14, 15 and 16, and in which plate 16 is mounted flush with the edge of the sash. The plate 16 of each hardware fitting is set into the edge of the sash member 5 adjacent the extreme upper transverse edge thereof designated at 19. The plate 16 carries a pair of spaced cam members represented at 17 and 18. Correspondingly, hardware plates 16 are mounted on opposite edges of window sash 4 immediately adjacent the extreme lower horizontal edge thereof designated at 20. Each of the sash strips carry coacting plates 21 transversely aligned with the plates 16 in the sashes. The plates 21 each include an annular trackway 22 into which the cam members 17 and 18 are adapted to project when the sashes are tilted, as explained hereinafter. The plates 21 are each slotted as represented at 21a and 21b in a position centrally with respect to the sash strip, and provide recesses into which the cam members 17 and 18 on plates 16 extend when the sash is in vertical alignment with the sash strips. As the window sashes 4 and 5 are turned, the cam members 17 and 18 of plate 16 move out of the recesses 21a and 21b and revolve through annular trackway 22 as a guide for controlling the angular shifting of the window sashes. The annular surface of trackway 22 is milled to provide a friction bearing surface for the ends of cam members 17 and 18 so that the sashes 4 and 5 remain in the angular positions to which they are tilted for cleaning or for ventilating purposes.

The positions of the coacting plates 16 on the window sashes, and the coacting plates 21 on the sash strips, are selected so that sash 5 may revolve around a transverse axis designated at 23, while window sash 4 may revolve around a transverse axis 24, each of which are designated by dash-dot lines in Fig. 1. These transverse axes 23 and 24 are disposed in such close proximity to the upper ends of the sash strips 6 and 7 and the lower ends of the sash strips 8 and 9 that the window sashes extend outwardly in a very restricted path, as represented more particularly in Figs. 2 and 5 wherein the window sashes 4 and 5 are angularly adjustable without offering any obstruction or interference to the storm window 25 set or mounted exteriorly of the window frame 1.

The storm window 25 is of conventional type adapted to interchangeably receive a screen for summer installation, or a glass window for winter installation. In either case the outward projection of the window sashes 4 and 5 is substantially nil, so that the window sashes are adjustable throughout their entire range of angular movement without interference with the permanently installed screen or window in the storm window frame 25.

There are definite advantages in enabling the window sashes to be adjusted inwardly, particularly with the composite vertical and angular movement which is possible in the arrangement of my invention, in that both sides of the window sashes become available at the interior of the installation for washing and cleaning without the necessity of stretching around the window sash or working exteriorly of the window sash, and proper ventilation may be secured by the desired angular setting of the sashes.

The manner of adapting weather stripping members to the improved composite sliding and swinging window sashes of my invention is a particular feature of my invention. In my improved arrangement the weather stripping member is not carried by the window sashes, but on the contrary is mounted in each sash strip. The construction is more clearly illustrated in Figs. 7 and 8 from which it will be seen that the sash strip 6, for example, is longitudinally slotted at 6a through which the weather stripping member 26 extends. The weather stripping member 26 carries a felt edging 27 which is adapted to be projected with the weather stripping member 26 into the groove 28 formed in the edge of the sash 5. The groove 28 is slightly offset in the edge of the sash 5 to provide adequate clearance for the actuating means designated at 29.

40 The sashes are trimmed for installation in the converted arrangement of sashes by grooving the edges thereof as designated at 28 in alignment with the projectable and retractible weather stripping member 26.

45 The controlling means for governing the projection and retraction of the weather stripping members are represented as extending from the tops of the sash strips at 30, 31, 32 and 33. The controlling means are shown more clearly in Figs. 5, 6, 7 and 8 and include a manually liftable element 34 secured to the weather stripping member 26 operating in slot 6a in sash strip 6. By lifting the manually liftable element 34 the weather stripping member 26 is projected into the aligned groove 28. This is accomplished by the arrangement of inclined cam slots 35 and 36 formed in the weather stripping member 25 and which ride upon pins 37 and 38 extending through the sash strip 6. Downward movement of manually liftable element 34 effects a retraction of weather stripping member 26 which returns to and is housed within the coacting groove 6a in the sash strip 6.

When the manually liftable element 34 is moved 65 to its extreme upward position the end of liftable element is angularly revolved to engage an abutment stop 39 on sash strip 6, thereby maintaining the weather stripping member 26 in projected position. The abutment stops 39 extend upwardly from the upper ends of the sash strips and have a width approximately equal to one-half the width of the sash strips. The stops 39 constitute raised abutments with respect to the tops of the sash strips and the manually liftable elements 34 are linearly movable adjacent one side

of the raised abutments 39 and are oriented so that portions of the liftable elements 34 may be confined by the tops of the raised abutments. This movement is made possible by the fact that liftable element 34 is connected to the coating sash strip through a swivel connection designated at 34a.

The manually liftable elements 34 of the control means 32 and 33 for the lower sash 5 are readily accessible. However, the comparable manually liftable elements 34 of the control means 30 and 31 are normally protected by the provision of pocket recesses 40 and 41 in the upper portion of the window frame 1. When the window is in closed position, control means 30 and 31 are housed in these recesses. The upper sash 5 is lowered, however, when it is desired to actuate the manually liftable elements 34 for controlling the position of the weather stripping members with respect to the edges of sash 5.

In Figs. 14-16 I have illustrated in detail the construction of the hardware fitting which is attached to opposite edges of the sashes. It will be observed that the plate 16 is substantially H-shaped with cam members 17 and 18 projecting transversely at spaced positions in alignment with the trackway 22 of the hardware fitting shown in Figs. 17-20.

The hardware fitting illustrated in Figs. 17-20 is also of H-shape contour in that the plate 21 is slotted in central vertical positions indicated at 21a and 21b leaving a central circular portion within the annular trackway 22. As heretofore noted the annular trackway 22 is milled or roughened to provide friction grip surface against which the cam members 17 and 18 rub in the course of angular movement of the sashes enabling the sashes to be maintained in the positions to which they are moved. It is to be emphasized that the improved construction of my invention enables the sashes 4 and 5 to be angularly adjusted to positions extending interiorly of the building structure as illustrated in dotted lines in Fig. 2 and in full lines in Figs. 5 and 12 without interfering with the composition storm window or screen 25, thereby rendering the structure of my invention highly practicable and convenient for use.

I realize that various modifications of my invention may be made and I desire that it be understood that no limitations upon my invention are intended other than may be imposed by the scope of the appended claims.

What I claim as new and desire to secure by Letters Patent of the United States is as follows:

1. A composite double hung and swinging window comprising a window frame having a pair of stiles, sets of sash strips slideable in said stiles, a window sash disposed between each set of sash strips, means for pivoting the window sashes on horizontal axes adjacent the top and bottom of said sets of sash strips whereby said window sashes are swingable through varying angles from a vertical position to a substantially horizontal position with said sashes extending an inappreciable distance beyond said stiles in one direction, the opposite edges of said window sashes each being slotted and said sash strips having slots therein vertically aligned with the slots in the edges of said sashes, weather stripping members housed within the slots of said sash strips, and control means disposed adjacent the tops of each of said sash strips and connected with the weather stripping members housed within the slots of said sash strips, said control means be-

ing vertically displaceable with respect to the top of the associated sash strip in a linear direction aligned with the axis of the associated sash strip for effecting projection or retraction of the weather stripping member with respect to said sash strips, and means for latching the weather stripping members in projected position with respect to the slots in the edges of said sashes, said means including a raised abutment carried by said sash strips over which said control means are confined when said control means are raised and oriented with respect to said raised abutments.

2. A composite double hung and swinging window comprising a window frame having a pair of stiles, sets of sash strips slideable in said stiles, a window sash disposed between each set of sash strips, means for pivoting the window sashes on horizontal axes adjacent the top and bottom of said sets of sash strips whereby said window sashes are swingable through varying angles from a vertical position to a substantially horizontal position with said sashes extending an inappreciable distance beyond said stiles in one direction, the opposite edges of said window sashes each being slotted and said sash strips having slots therein vertically aligned with the slots in the edges of said sashes, weather stripping members housed within the slots of said sash strips, and control means disposed adjacent the tops of each of said sash strips and connected with the weather stripping members housed within the slots of said sash strips, said control means being vertically displaceable with respect to the top of the associated sash strip in a linear direction aligned with the axis of said sash strip for effecting projection or retraction of the weather stripping member with respect to said sash strips, the upper portion of said window frame immediately over said sash strips having a pair of socket recesses therein, for receiving the control means extending from the upper ends of the sash strips associated with the upper window sash when the upper window sash is moved to its extreme upper position within said window frame.

3. A composite double hung and swinging window as set forth in claim 2, in which the control means carried by said sash strips comprise angularly movable lever members movable about axes extending longitudinally through said sash strips for effecting projection and retraction of the weather stripping members.

4. A composite double hung and swinging window as set forth in claim 1 in which said raised abutments extend approximately one-half the width of the upper ends of said sash strips and wherein the control means are linearly movable adjacent one side of the raised abutments and are orientable to positions in which portions of the control means extend transversely across the tops of the raised abutments.
